ALEXIS SZABO, OF CLUJ, BUMANIA, ASSIGNOR OF ONE-FOURTH TO JACOB SCHOBEL,
OF NEW YORK, N. Y.

COLOR-PRINTING MACHINE.

Application filed February 18, 1927, Serial No. 169,285, and in Hungary June 24, 1925.

My invention relates to improvements in color-printing machines and has for one object to largely reduce the printing operations such as the change of the printing base 5 coatings (several layers of papers) and the adjustment of the printing block after each succeeding color, thereby to largely reduce the expense involved in color printing and thus increase the popularity of its use in the 10 production of artistic products. Another object is to provide a color-printing press of simple construction and to reduce in this way the costs of the machine itself thereby further contributing to the cheapness of the 15 products in question.

The process of color-printing is one of the most important and hard problems of the printing arts and though there is a large demand for color-printed products, efforts to 20 solve the problems in a satisfactory manner from a technical and economical standpoint have not succeeded. It has been already proposed to provide color-printing machines in which a plurality of printing tables or printing 25 bases, at least as many as colors are required, and of printing blocks, are arranged circumferentially and in equally spaced positions around a common axis. But in one kind of these machines the printing bases 30 were rotated around the common center to bring each printing base or plate, together with the sheet of paper to be printed, into cooperation with the radially movable printing blocks. This arrangement is very unsatisfactory from the practical point of view 35 because each printing base must be, previous to the printing operation, brought in precise conformity to the corresponding printing block by the most difficult and careful 40 preparatory operations (coating and adjustments) but this conformity being annulled by the next rotation of the printing base towards another printing block, requiring another adjustment, the arrangement results 45 in useless spotted products especially in the case of finer color-printed matters.

In another kind of the color-printing machines hitherto known, in which a particular rotatable clamping disc, using as many paper 50 clamping or gripping means as there are printing tables or bases, is provided for supporting and periodically moving the sheets of paper in a circle and from one printing place to the next, the above mentioned disad-

vantage of the rotation of the printing bases 55 could be eliminated. In such an arrangement, notwithstanding that the printing bases are raised at each printing operation toward the above arranged and fixed printed blocks and then lowered, this arrangement 60 has the disadvantage of further increasing the weight of the printing tables (already being too heavy originally) by additional driving parts; besides, the whole machine must have been constructed stronger and therefore 65 made more expensive on account of the larger masses being moved and also of the fact that the weighted printing tables cause a quicker and greater wear on the corresponding meshing 70 parts and bearings. This results in the alteration of the above mentioned important adjustment or registering of the printing bases with the printing blocks which alteration is much more marked than it would be in the event of moving the much lighter 75 printing blocks. Furthermore, the paper clamping disc having been lifted and lowered together with the printing bases, the whole arrangement and the driving apparatus 80 of the machine becomes very complicated and consequently the costs of manufacturing of the machine are substantially increased and the duration of the same decreased. Besides this, frequent interruptions 85 of the operation occur and all these disadvantages have prevented the very desirable propagation of machines of this type in practice.

Again, in other types of color-printing presses, the printing bases are in a fixed position, an arrangement which is considered to be advantageous. However, the disc or ring carrying the sheets of paper is suspended 90 rotatably upon the vertically movable frame of the printing forms so that the said disc or ring is moved, in addition to its periodical rotation, also in a vertical direction, or at least the proper individual carrying frame of each of the sheets of paper is moved vertically, at each stroke of the printing forms 95 to bring the sheet of paper into the level of or upon the printing base. In both cases additional guiding arrangements are to be provided and the additional vertical movement of the sheets introduces a factor of inaccuracy 100 in printing which becomes more increased by the wearing of the additional guiding arrangements.

My invention has for its object to provide a color-printing press meeting all practical requirements and eliminating perfectly all the said disadvantages. According to my 5 invention, this result will be reached by providing a clamping or gripping device in the form of a disc carrying the sheets of paper and cooperating with fixed printing bases in such manner that the said disc and the sheets 10 of paper move exclusively in a circle with the disc and the sheets constantly in the same level or plane, which corresponds to the constant level of the fixed printing bases. This enables a substantial simplification of 15 the arrangement and the driving of the sheet carriers and insures the best accuracy of printing and also makes the outer surfaces of the central upright frame freely susceptible of several arrangements. The interior 20 of this frame, around which all parts assisting in the printing operation are arranged, is available, in a known manner, for the reception of the common slide bar driving the printing blocks to be lifted and lowered according to the invention, and through the 25 said outer surfaces of the central frame there are supported and guided, by means of suitable recesses, the moving devices of the abutting elements of the sheets of paper and of 30 sheet gripping and retaining parts and also the rod system driving, from beneath, the color-printing or inking rollers.

All these arrangements and constructions 35 result in such substantial simplification and economical space utilization and in such compendious form as to make the machine no more complicated than most of the one-color-printing machines used at present.

A further object of my invention is to provide 40 an arrangement which enables certain preparatory steps of the printing operation (adjustments, laying of the coating sheets of the printing base) to be carried out in a quick and comfortable manner. This object 45 is obtained according to the invention by means of a common annular frame-part carrying the printing bases, ordinarily in fixed position during the printing operation, which frame may be, if desired, rotated at will and 50 by hand i. e. adjusted to the left or right, so that any one printing base may be brought to the same place, namely before the seat of the operator where the laying of the coating or registering sheets of all printing bases 55 may be subsequently carried out in a comfortable manner. By the rotation of the said common annular frame of the printing bases the printing blocks, which are above the printing bases and therefore ordinarily not 60 accessible, also will be exposed for free access. It is unnecessary, in connection with this arrangement, to make the frame part carrying the printing blocks likewise rotatable, which 65 would make the machine more complicated, because adjustments of said blocks need be

made only on one side by other workmen while the adjustment of the printing bases may be accomplished at the operator's seat O.

My invention is illustrated more or less diagrammatically in the accompanying 70 drawings, wherein:

Figure 1 is a side elevation of the machine, partly broken away and shown in section.

Figure 2 is a plan view in partial horizontal section showing the printing bases and the device for gripping and moving the sheets of paper, the upper parts (printing blocks and inking devices) being removed.

Figure 3 is a similar view of the lower part 75 of the machine showing the several driving and controlling means. Figure 3^a is a reduced partial side elevation of the driving means of the common rack controlling the inking rollers.

Figure 4 is a side elevation of the driving system of the color printing or inking rollers.

Figure 5 is a plan view of the driving system of all color distributing and printing 80 rollers.

Figures 6 to 11 show details partly on a larger scale, namely:

Figure 6 is a side elevation of the controlling devices of the abutting and gripping 85 elements of the sheets of paper.

Figures 7 and 8 are a side elevation and a plan view, respectively, of one of the sheet gripping elements.

Figure 9 is a side elevation of the controlling means of the side guide of the sheet of 90 paper and

Figures 10 and 11 are a side elevation and a plan view, respectively, of one pair of the sheet retaining bars.

The main parts of the illustrated machine 105 are as follows:

A is a central vertical frame, (see Figure 1), fixed on a foot 2 resting on the base plate 1 of the machine. Printing bases B₁, B₂, B₃, (see Figure 2) are arranged, together with a platen B₀ before which the operator is located, equal distances apart, and upon an annular frame B disposed around the said central frame A, said bases being in fixed position during the operation. Printing blocks or 110 forms C₁, C₂, C₃ together with their frames are located directly above the bases B₁, B₂ and B₃, respectively, the base B₂ and its accompanying block C₂ being located behind the center frame A in Fig. 1. A common slide E, 115 (see Figure 1) is guided in the interior of the central frame A, and operates all the printing blocks C₁, C₂, C₃ simultaneously by lifting and lowering the same above the printing bases B₁, B₂, B₃. A conveying wheel D is 120 rotated around the central frame and carries, by means of the sheet gripping devices F, (see Figures 2, 7 and 8) the sheets of paper to be printed and successively positions the same, by periodical and partial rotation, upon 125 130

the printing bases B_1, B_2, B_3 where the sheets are to be printed with the several colors. A fixed supporting plate G is mounted upon the upper part of the central frame A and carries 5 the operating rod system of the printing blocks C_1, C_2, C_3 and the driving means of the groups of color distributing rollers K_1, K_2, K_3 and of color printing or inking rollers L_1, L_2, L_3 (see Figures 1, 4 and 5). All of the latter rollers coat the lower surface of the printing blocks with color and are driven by a common rack H (see Figures 4, 5 and 3^a) guided and raised in a recess a_4 (see Figure 3) of the central frame A itself. The middle 15 group L_2 of the color printing rollers (not shown) is intended to be above the printing base B_2 . A sheet abutment or stop J (see Figures 2, 6 and 7) which in cooperation with the side abutment S for the lateral limiting 20 of the sheet of paper, see Figures 2 and 9, determines the required position of the new sheet of paper introduced on the platen B_0 . These abutments J and S are according to the invention, raised and lowered automatically, 25 by means of a particular controlling device, to enable the paper conveying wheel D to perform its movement without any obstacle. Sheet retaining bars R by means of which the sheet of paper is kept down during each printing 30 operation in known manner, are moved upwardly after each operation and, according to my invention, the extent of movement is such that said bars R move out of the path of the paper conveying wheel D so that the latter 35 may freely and periodically rotate. The operating device for the bars R are arranged in suitable recesses a_1 (see Figures 2 and 3) of the central frame A itself. Finally, a main driving mechanism $N, M_1, M_2, \dots$ etc. is 40 mounted adjacent the foot 2 of the machine and is utilized to control and drive the several parts of the machine. The construction and relative arrangement of all the main parts hereinbefore referred to will now be described 45 in a more detailed manner:

The annular frame B (see Figures 1 and 2) carrying the platen (paper introduction and delivering table) B_0 and the printing bases B_1, B_2, B_3 is mounted upon uprights 3 fixed on 50 the base plate 1 of the machine. This frame B is in a fixed position during the operation but may be swung before the beginning of the printing operations to the right or left for the carrying out of the preliminary operations above mentioned. For this purpose the under side of the frame B is provided with rails or bars 8 slideable upon concentric ribs 9 formed on the upper end of the uprights 3, the annular frame B being circumferentially 55 toothed as at 10 to mesh with the toothed rim of the hand wheel 13 (see Figure 3). The latter is provided with a vertical handle 12 through which the hand wheel may be rotated in any direction and to any extent at will and 60 thereby the frame B may be swung in such a

way that one or the other of the printing bases B_1, B_2, B_3 may be brought into the original place of the platen B_0 , as shown in Figure 2, in front of which there is the seat O of the operator, so that the coatings of all printing 70 bases may be changed at the same place without the necessity of the operator leaving his seat. At the same time the printing blocks C_1, C_2, C_3 become easily accessible from beneath and consequently the adjustment of the printing blocks, etc. may be carried out without any trouble and properly by other workmen at the same period during which the coatings of the printing bases are changed by the operator of the machine. After the carrying out of the steps preliminary to the printing operation the annular frame B may be brought into the operating position according to the Figure 2 by means of the hand 75 wheel 13.

For the purpose of periodically conveying the sheet of paper I provide, as already mentioned, a wheel D (see Figures 1 and 2) the axis of rotation of which is formed by the central frame itself, the edges of the latter being, 80 for this purpose, conveniently rounded off according to the form of the wheel D , as shown in Figure 2. The lower part of the wheel D rotatable around this central frame is formed as a beveled gear 5 (see Figure 1) the lower 85 surface of which rests upon rollers 6 mounted upon the sides of the central frame A by means of fixed bearings so that the wheel D rolls during its rotation upon these rollers to reduce the friction. The beveled gear 5 meshes with a similar gear 7 arranged on a horizontal shaft (see Figures 1 and 3) and provided only in places with teeth i. e. there are toothed 90 arcs alternating with smooth parts in such a manner that the wheel D makes periodically 95 a quarter of a revolution to slip the sheets of paper held by means of the gripping devices F to be described, mounted upon its upper side, one after the other over the surface of the printing bases B_1, B_2, B_3 and to hold 100 them during the printing operation upon the printing base whereupon a further quarter of a revolution takes place and so forth. For the same purpose, forms of transmission 105 gears, such as a ratchet and ratchet-wheel, 110 may be used.

In the cavity a provided in the interior of the central frame A (see Figure 2) a common slide E (see Figure 1) is guided which serves, as already mentioned, for the simultaneous 115 raising and lowering of all printing blocks. For this purpose there is carried by the upper end of the slide a horizontal plate 14 upon which pins 15, one for each printing block, are mounted. Each pin 15 penetrates a slot 120 formed in the inner end of a lever 16 rotatable around a shaft 17 having a fixed bearing mounted upon a supporting plate G fixed upon the upper end of the central frame A . The outer end of each lever 16 being likewise 125

130

slotted is connected with a horizontal pin 18 fixed upon a cross bar 22 (see mid upper part of Figure 1) which is arranged between vertical rods 19 carrying the frame of the printing block C_1 or C_2 or C_3 . The rods 19 being moved in this way in a vertical direction are guided partly in the plate G and partly by consoles 21 fixed upon the under side of the plate G. A cross frame between the vertical rods 19 is in connection with an eccentric collar surrounding an adjusting and stopping eccentric 20, all this in substantially known manner. By means of this eccentric the rods 19 together with the printing block 15 and its frame may be lifted independently of the operating device in such a manner that the printing block cannot reach the printing base even in the lowest position of the operated lever 16; in this way one or the other of the 20 printing blocks may be, if desired, taken off from the printing operation or the stroke of the printing block regulated at will. This eccentric device serving for the purpose of adjustments and stopping being well known in 25 other printing machines a further description of the same is not required but it will be noted that the use of this adjusting device in connection with the machine according to the invention may be, besides, used also for the 30 further event if in the single color printing, urgent work is to be carried out very rapidly; in such case one of the printing blocks, by means of which one printing operation is just in the course of completion, may be simply 35 taken off from printing without the necessity of changing this block and of varying the coatings of the base whereupon the printing block according to the new urgent work will be inserted into one of the free block frames 40 C_1 or C_2 or C_3 .

The common slide E is provided at its lower end with a rhombic articulated rod system 23 the side articulations 24 of which, or rollers mounted upon these articulations, are 45 actuated for the purpose of raising the slide E by cams e the driving of which will be described later.

For limiting the position of the sheet of paper to be set, in front of the platen B_0 , and 50 over the surface of the conveying wheel D, there are provided, as already mentioned, an abutment J and side abutment S regularly controlled so as to enable the wheel D to make its quarters of revolution together with the 55 sheet of paper after the insertion and gripping of the latter. According to this condition the abutment T is constructed and controlled in the following manner, also as shown in Figure 6.

60 The proper abutment J consisting of a horizontal bar portion resting upon the platen B_0 , is carried by a bar 25 bent off at right angle and branched off from a vertical rod 26 (see Figures 2 and 6). This rod 26 is 65 guided in a recess a_2 of the central frame A

itself and connected at its lower end with a link 27 articulated upon a two-arm lever 28 the bearing of which is mounted upon the foot 2 of the machine. The underside of the outer arm of the lever 28 is acted upon by a cam j fixed upon the shaft M_1 (see Figures 3 and 6) while the outer end of this lever is under the action of a spring 29. The construction and the driving of the cam j , this driving being described later more particularly, is accomplished in such a manner that always the sheet of paper the printing of which is finished and which is then carried by the wheel D from the printing base B_1 to the platen B_0 and released as described below, may be withdrawn by the operator each time the left hand arm of the lever 28 is lifted by the cam j against the action of the spring 29. Thereby the rod 26 is lowered, together with the abutment J, so that the latter will be resting upon the platen B_0 and consequently ready for the proper positioning of the new sheet of paper. After some moments during which the insertion of the new paper by the operator and the gripping of this paper by the gripping device F has taken place, the lower portion of the cam j reaches the underside of the lever 28 causing the lowering of the outer arm of this lever by the spring 29 and the consequent lifting of the bars 27, 26 and 25, together with the abutment J, so that the path of the sheet of paper becomes entirely free. Simultaneously with the control of the abutment J there takes place also the control 95 of the side abutment S, (see Figures 2 and 9) but with the difference that the withdrawal of this side abutment out of the operating position or of the path of the sheet of paper is not carried out by lifting but by lowering below the platen B_0 . For this purpose the 100 proper side abutment S consists of a block mounted upon the upper end of a vertical rod 55, both passing through a slot 54 of the platen B_0 . The abutment S is slidable sideways in horizontal direction (not shown) to 105 accommodate itself to the varying size of paper and may be fixed in the adjusted position in any suitable way.

The rod 55 is guided in vertical guides mounted upon the frame of the machine and bent off at right angle at its lower end, the latter carrying a roller 56 which cooperates with a cam s (see Figure 3) fixed upon the shaft M_1 , so that when a new sheet of paper is inserted, the rod 55—together with side abutment S—is raised by the cam s in the operating position. There, namely shortly before the wheel D is again rotated together with sheet of paper towards the printing base B_1 , the lower part of the cam s turns under the roller 56 whereby the abutment S and the rod 55 are lowered under the action of a spring or of the weight of the rod system, below the platen B_0 .

For the purpose of gripping the sheets of 130

paper to be revolved by quarters of a revolution, each of the four plates d (see Figure 2) arranged in a circle at equal distances apart, carries a gripping device F the construction and control of which are as follows (see Figures 7, 8 and 6).

Each gripping element as such consists of two jaws 37, 38 movable one towards the other like a clamp. The fixed lower jaw 38 is mounted upon the plate d whereas the upper jaw consists of a two arm lever articulated on the lower jaw. Between the two jaws 37, 38 there is a leaf spring 39 having the tendency to hold the clamp constantly in the closed position. When the wheel D carrying the sheet of paper, the printing of which was just finished, moves away from the printing base B_3 and reaches the platen B_0 , the elongated arm of the jaw 37 comes underneath a roller 32 (see Figures 6 and 7) carried by a bar 30. This bar 30 which is bent two fold at right angles (see Figures 6 and 8) is fixed upon a vertical rod 33 guided in a recess a_3 of the central frame itself (see Figure 3) and connected at its lower end by a link 34 with a device similar to the controlling means of the abutment J i. e. with a two arm lever 35 which is likewise rotatably mounted upon the foot 2 of the machine. The outer free arm of this lever is acted upon from underneath by a cam f and a spring 36 in such a manner that when the gripping device F reaches the platen B_0 the outer arm of the lever 35 is raised by the cam f and consequently the roller 32 is lowered so that the clamp 37, 38 is opened and therefore the operator may withdraw the finished printed sheet of paper. The gripping device or clamp rests, in some instances in the opened position. Meanwhile the abutment J has been lowered and pressed against the platen B_0 . At the same time the inner edge of the sheet of paper inserted by the operator toward the abutment J is passing over the free end of the lower jaw 38 of the clamp whereupon the lower portion of the cam f passes below the outer arm of the lever 35 causing the lowering of this outer arm by the spring 36 and therefore the raising of the roller 32. At this instant the outer end 31 of the upper jaw 37 of the clamp strikes again, under the action of the spring 39, upon the edge of the inserted sheet of paper so that the latter will be gripped. Preferably the upper jaw or both jaws of the clamp are twofold ones (see Figure 8) so that the sheet will be gripped at two places by the gripping device. For enabling a free motion of the outer ends of the clamp the horizontal bar forming the abutment J is somewhat bent upwards at its central portion as shown in Figure 6. The cam f , the driving of which will be described later, is fixed upon a shaft M_1 common to the cams j and f .

The arrangement of the devices provided for the driving and control of the several

parts described above, is shown in Figure 3. According to this figure the shaft of a pulley N placed at the lower end of the frame of the machine and driven from any source of power, carries a gear wheel 40 meshing with a gear wheel 41 for the driving of the control shaft M_1 . From the latter and by means of chain pulleys or strap-wheels 42, 44 and a cross chain or strap 43 the second control shaft M_2 , parallel to shaft M_1 is driven. Upon the control shafts M_1 , M_2 there are keyed the opposed cams e , equal in size and operating the common slide E (see Figure 1) symmetrically for the purpose of carrying out the printing operation i. e. for lowering the printing blocks C_1 , C_2 , C_3 . For this purpose the side articulations 24 of the articulated rod system 23 are pressed inwardly by the projecting portions of these cams e whereby the rod system will be moved upwardly and consequently the slide E raised, whereas the lifting of the printing blocks i. e. the lowering of the slide E , during the passing away of the projecting portions of the cams e from the articulations 24, is effected by the weight of the rod system assisted by springs, if desired.

Upon the said control shaft M_1 there are further keyed the cam f for the control of the sheet gripping device F , the cam j for the control of the abutment J and the cam s for the control of the side abutment S .

Cooperating with each printing base B_1 , B_2 , B_3 pairs of sheet retaining bars R are provided. For the sake of clearness only one pair of these bars is shown in Figure 2. Each pair of these bars arranged on the side walls of the central frame A may be elevated and is controlled in such a way that immediately before the printing operation begins, the bars R fall upon the sheet of paper and hold it down for the purpose of preventing the adherence of the sheet of paper to the block when raising the latter whereas after the raising of the printing block the bars R are swung upwardly to give free path for the wheel D and the sheet of paper moving again through a quarter of a revolution. Each pair of bars R in order to have as hereinbefore mentioned, a swinging arrangement on the sides of the central frame A , is mounted for this purpose upon brackets 51 (see Figures 10 and 11) fixed upon the side walls of the central frame whereas all of the control rods of the sheet retaining bars are arranged in recesses a_1 of the central frame A itself. For enabling an adjustment of the sheet retaining means according to the several lengths of the sheets of paper the cross portions of these bars which are bent at right angles, may be formed telescopically (not shown) so that the distance between the two parallel bars of a pair may be adjusted at will and the pair fixed in the adjusted position in any suitable manner. The control device of these sheet retaining bars comprises, in the first place, a roll-

er 52 acting upon the middle point of the cross portion of the bail-like inner arm 53 (see Fig. 11) of the pair of bars arranged as a two arm lever, the said roller 52 being carried by an arm 50. The latter is fixed upon a vertical rod 49 guided in the above mentioned recess a_1 and acted upon by one or the other of cams r_1 , r_2 , or r_3 respectively, the cam r_1 which operates the rod 49 of the certain sheet retaining device belonging to the printing base B_1 , being mounted upon the shaft M_1 and the cam r_3 , cooperating with the pair of bars R belonging to the printing base B_2 , being mounted upon the control shaft M_2 , whereas the cam r_2 controlling the pair of bars R belonging to the printing base B_2 is fixed upon an auxiliary shaft 48, driven by the control shaft M_2 , by means of beveled gear wheels 46 and 47.

If desired, the controlling arms 50 of the pairs of bars R may be connected one with the other by means of a common movable frame surrounding the central frame A for example and provided with a driving lever for example, acted upon by a single controlling cam, by which arrangement all of the pairs of bars R will be controlled by a common cam, of course.

Upon the shaft of the pulley N (see Figure 3) is further mounted the bevel gear wheel 7 serving, as above described, for the driving of the sheet conveying wheel D whereas the end of the shaft M_1 opposite to the cam s carries a bevel gear wheel 57 driving, by means of a bevel gear wheel 59^a, a vertical shaft 58 serving to operate the color distributing rollers and carrying for this purpose at the upper end a bevel gear wheel 59^b (see Figure 5) meshing with a bevel gear wheel 60. The latter is fixed upon a shaft k_2 , the bearings of which are mounted upon the above mentioned supporting plate G. Through this shaft k_2 and by means of a spur gear wheel 61 and further small gear wheels usually employed (not shown), there are driven the color distributing rollers K_2 whereas on the ends of the shaft k_2 bevel gear wheels 62, 65 are provided, the wheel 62 meshing with a similar wheel 63 of the shaft k_1 and wheel 65 with a similar wheel 66 of the shaft k_3 . The said shaft k_1 serves, by means of a spur gear wheel 64 and further small gear wheels, through which the adjacent rollers drive one another, to drive the color distributing rollers K_1 and—similarly—the shaft k_3 serves, by means of a spur gear wheel 67 and further small gear wheels, to drive the color distributing rollers K_3 . As will be seen, there is derived from the shaft k_2 the driving of all of the sets K_1 , K_2 , K_3 of color distributing rollers. These sets of rollers are arranged in fixed bearings mounted upon the frame of the machine in arms for example (not shown) which are fixed on the uprights 3 (see Figure 1). These color distributing rollers 65 serve the usual purpose of transmitting the

color, taken up and rubbed also in known manner, upon the sets of inking rollers L_1 , L_2 , L_3 alternately swinging under the action of beam lever frames l_1 , l_2 , l_3 below the printing blocks C_1 , C_2 , C_3 and coating the lower (printing) surfaces of these blocks with color. For this purpose the inking rollers, which are resiliently mounted, in known manner in recesses or slots of the forked lower end of the said levers l_1 , l_2 , l_3 , for rotation around a shaft 68 mounted upon the supporting plate G, are provided with the following driving mechanism:

In a recess a_2 (see Figure 3) of the central frame A a bar H (see Figures 4 and 5) common to all of the inking rollers is guided, the lower portion of which being provided, as will be seen in Figure 3^a, with a laterally projecting frame 45; in the opening of the latter an eccentric h is rotating which is fixed on the control shaft M_2 (see Figure 3) and the frame 45 itself is guided in vertical guides (not shown). The bar H, which reciprocates vertically under the action of the eccentric h , is formed at its upper end as a rack meshing with a toothed wheel 76 (see Figures 4 and 5) which is mounted upon a shaft 77 the bearings of which are carried by the upper supporting plate G. This shaft 77 is provided at both ends with bevel gear wheels 78 driving, by means of similar wheels 79, two parallel shafts 80 mounted likewise upon the said supporting plate G. Each of the shafts 80 carries a cam 75 (see Figure 4) acting upon the upper pin 74 of a two arm lever 73 rotatable on the shaft 72 mounted in bearings fixed on the supporting plate G. The lever 73 is connected by a link 71 to a lever 70 rotatable on a shaft 70^a mounted in fixed bearings on the supporting plate G, the upper slotted end of this lever 70 being in connection with the upper shorter arm of the above mentioned lever l_1 or l_3 . On the shaft 77 (see Figure 5) is also fixed a chain-pulley 81 driving, by means of a chain 82 and a chain-pulley 83, a shaft 85 arranged in bearings fixed on the supporting plate G, the shaft 85 carrying a cam 75 driving, by means of a mechanism 70, 71 . . . 74 similar to that just described, the beam lever l_2 for the set of inking rollers L_2 . There is one of the above described driving mechanism for each of the two beam levers l_1 , l_2 , l_3 associated with each set of the inking rollers L_1 , L_2 , L_3 , which rollers swing in one direction under the action of the projecting portion of the cams 75 moved by the rack H, and swing in the other direction under the action of usual springs (not shown) during the period in which the lower portions of the cams pass the pins 74 and in which the printing blocks are inked, whereupon the inking rollers return to their original or color receiving position according to Figure 4 each time before the printing operation begins.

The operation and use of the machine above described is as follows:

When the printing of the sheet of paper with three colors is finished (at B₃), the same is carried by the wheel D—with a quarter of a revolution—back to the platen B₀, i. e. the starting point of its whole revolution and the side abutment S will be raised and the abutment J lowered to the surface of the platen B₀ under the action of the controlling mechanism above described. Immediately thereafter the sheet gripping means F become opened, the inking rollers operated and during the period in which the printing forms 10 are inked by these rollers and the latter returned to the color distributing rollers K₁, K₂, K₃, the operator removes the finished copy, sets it onto the depositing table P₂ (see Figure 2), takes up a new sheet of paper 15 from the storage table P₁ and inserts it upon the platen B₀. After the inking of the printing forms or blocks the sheet gripping means F become closed and remain in closed position until they reach the platen B₀ again 20 after a whole revolution of the wheel D. At the platen and after the closing of the gripping device F the abutment bar J is raised but the side abutment S lowered to make free path for the sheet of paper beginning its 25 revolution; the wheel D makes a quarter of a revolution towards the printing base B₁ and positions the sheet of paper, which it has conveyed about a quarter of a circle, readily in the plane of the same upon the coating of 30 the printing base B₁ whereupon the wheel D is stopped so that the printing with one of the colors required may be effected. The sheet of paper being at this point printed with one of the colors is conveyed to the printing base B₂ and the same sheet being printed 35 at this place with two colors already, is transmitted to the printing base B₃. At each printing base the sheets of paper inserted each after the other at the platen B₀ and 40 conveyed towards the several printing bases are pressed down by the sheet retaining bars R controlled in the manner described for the period of the printing operation and for the purpose above mentioned. At each stopping 45 of the wheel D all of the three printing forms C₁, C₂, C₃ are moved simultaneously by the common slide E, so that the printing of the sheets of paper lying on the several printing bases with the first, second or third color 50 respectively, is carried out simultaneously. This whole process, namely the progressive manufacturing of the copy and the repetition 55 of the operation requires, after the foregoing statements, no further description. Similarly it is clear that the construction and the relative arrangement of the several driving and controlling parts is chosen on the basis of 60 constructional methods well known to those skilled in the art, in such a way that the several phases of the operation have the de-

scribed time relation in respect to each other.

The machine according to my invention is applicable with great advantage not only for printing establishments as such but also for bookbinderies and is especially adapted for carrying out the gilding or different coloring of book-covers and other printing operations such as text and artistic decoration in gold or other colors, warm and cold blank-printing. By the use of the present machine, the several printing operations capable of being performed thereby may be carried out more rapidly than with the bookbinder gild-press or the like hitherto known. The operation in connection with the latter is a very fatiguing and long-lasting one: in the first instance, each color is to be printed one after the other and the plate upon which the types and stereos or clichés are glued is to be pushed out after each printing and then raised and inked by means of the hand roller, whereupon it is to be re-inserted and so forth. By the use of the machine according to the invention this long-lasting process is avoided as will be seen clearly from the operation described above.

When, in the case of mistakenly inserted sheets of paper or other disturbances of the operation, a quick stopping of the machine or some main parts thereof is required, couplings of known character, actuated by a hand or foot lever, enabling a ready engagement or disengagement may be used, for instance, upon the shafts M₁, M₂ to disconnect the slide E and thus also the printing forms. Further for the disconnection of the driving of the conveying wheel D and the inking rollers, any brake devices for braking the large pulley N (see Figure 3) or a fly wheel may be provided.

What I claim is:

1. In a color-printing machine, the combination of a number of printing bases arranged equidistances apart in a circle around a common axis, the number of said bases being at least equal to the number of colors to be printed, a number of printing forms arranged equidistances apart in a circle coaxially with the said printing bases and movable to and fro in a direction perpendicular to the plane of the said circle, and a gripping device provided with means for gripping the sheets of paper to be printed, the said printing bases being fixed and said gripping device together with the sheets held thereby being moved exclusively in a circle and constantly in the same plane.

2. In a color-printing machine, the combination of a number of printing bases arranged equidistances apart in a circle around a common axis, the number of said bases being at least equal to the number of colors to be printed, a number of printing forms arranged equidistances apart in a circle coaxially with the said printing bases and movable to and

fro in a direction perpendicular to the plane of the said circle, a gripping disc provided with means for gripping the sheets of paper to be printed, the gripping disc being movable exclusively in a circle, a common movable frame for carrying said printing bases, and means for moving said frame whereby any one printing base brought into position for executing certain preparatory operations preceding the printing operation.

3. In a color-printing machine, the combination of a number of printing bases arranged equidistances apart in a circle around a common axis, the number of said bases being at least equal to the number of colors to be printed, a number of printing forms arranged equidistances apart in a circle coaxially with the said printing bases and movable to and fro in a direction perpendicular to the plane of said circle, a gripping disc provided with means for gripping the sheets of paper to be printed, the gripping disc being movable exclusively in a circle, a common movable frame for carrying said bases and rotatable around the said common axis, and means for moving said frame whereby any one printing base brought into position for executing certain preparatory operations preceding the printing operation.

30 4. In a color-printing machine, the combination of a number of printing bases arranged equidistances apart in a circle around a common axis, the number of bases being at least equal to the number of colors to be printed, a number of printing forms arranged equidistances apart in a circle coaxially with said printing bases and movable to and fro in a direction perpendicular to the plane of said circle, a gripping disc movable exclusively in a circle concentric with said circle and provided with means for gripping the sheets of paper to be printed, a common frame carrying the said printing bases, means to move said frame whereby any printing base may be brought into position for making certain preparatory operations preceding the printing operation, a plurality of sheet retaining bars connected to a common frame, and a single controlling device for said bars.

50 5. In a color-printing machine, the combination of a number of printing bases arranged equidistances apart in a circle around a common axis, the number of said bases being at least equal to the number of colors to be printed, a number of printing forms arranged equidistances apart in a circle coaxially with the said printing bases and movable to and fro in a direction perpendicular to the plane of said circle, a gripping disc movable exclusively in a circle concentric with said circle and provided with means for gripping the sheets of paper to be printed, a common frame rotatable around the common axis of said printing forms and gripping disc and carrying the said printing bases, means to

rotate said frame to bring any printing base into position for making certain preparatory operations preceding the printing operation, a plurality of sheet retaining bars connected to a common frame, and a single controlling device for said bars.

6. In a color-printing machine, the combination of a number of printing bases arranged equidistances apart in a circle around a common axis, the number of said bases being at least equal to the number of colors to be printed, a number of printing forms arranged equidistances apart in a circle coaxially with the said printing bases and movable to and fro in a direction perpendicular to the plane of said circle, a gripping disc movable exclusively in a circle concentric with said circle and provided with means for gripping the sheets of paper to be printed, a common frame carrying the said printing bases, means to move said frame to bring any printing base into position for making certain preparatory operations preceding the printing operation, a plurality of sheet retaining bars connected to a common frame, and a single controlling device for said bars, said retaining bars and controlling device being arranged inside and on the outer surface of a central main frame of the machine.

7. In a color-printing machine, the combination of a number of printing bases arranged equidistances apart in a circle around a common axis, the number of said bases being at least equal to the number of colors to be printed, a number of printing forms arranged equidistances apart in a circle coaxially with the said printing bases and movable to and fro in a direction perpendicular to the plane of said circle, a gripping disc movable exclusively in a circle concentric with said circle and provided with means for gripping the sheets of paper to be printed, a common frame carrying the said printing bases, means to move said frame to bring any printing base into position for making certain preparatory operations preceding the printing operation, a plurality of sheet retaining bars connected to a common frame, an abutment for the sheets of paper to be inserted, a side abutment for the sheets, and controlling rods for the sheet retaining bars, said abutments and the said gripping disc being arranged in recesses of the main frame of the machine.

8. In a color-printing machine, the combination of a number of printing bases arranged equidistances apart in a circle around a common axis, the number of said bases being at least equal to the number of colors to be printed, a number of printing forms arranged equidistances apart in a circle coaxially with the said printing bases and movable to and fro in a direction perpendicular to the plane of said circle, a gripping disc movable exclusively in a circle concentric

with said circle and provided with means for gripping the sheets of paper to be printed, a common frame carrying the said printing bases, means to move said frame to bring 5 any printing base into position for making certain preparatory operations preceding the printing operation, a plurality of sheet retaining bars connected to a common frame, a single controlling device for said bars, sets 10 of inking rollers for the several colors to be printed, a common driving rod for the simultaneous driving of all of the sets of inking

rollers, an abutment for the sheets of paper to be inserted, a side abutment for the sheets, and controlling rods for said abutments, 15 the said common driving rod of the inking rollers, the controlling device of the sheet retaining bars, and the controlling rods of said abutments being arranged in recesses of the main frame of the machine. 20

Signed at Bucharest, Rumania, this thirty-first day of January A. D. 1927.
